A wide band linear amplifier comprising first and second heavily damped Josephson devices and associated superconducting circuitry. Each Josephson device has a parallel path with a load resistor connected thereto. The parallel path connected to the first Josephson device is positioned to operate as a control current path for the second Josephson device. Both Josephson devices are operated on linear portions of their respective gain curves. The output current through the second load resistance is a linear amplification of the input current; the latter being applied as control current to the first Josephson device.

**HIGH GAIN, LARGE BANDWIDTH AMPLIFIER
BASED ON THE JOSEPHSON EFFECT**

This is a continuation of Ser. No. 319,588, filed 12/29/72, now abandoned.

BACKGROUND OF THE INVENTION

The invention is in the field of Josephson device circuits and more particularly is a wide band linear amplifier using Josephson devices.

As is well known in the art there is a class of cryogenic devices which are known as Josephson devices. The voltage across a Josephson device will remain at zero for applied currents up to a critical value I_m and will jump to a finite value for applied currents in excess of I_m . Additionally, the critical current I_m varies with magnetic field applied to the device. It is common in many applications to apply the magnetic field by passing a control current I_c through a superconductor overlying and electrically insulated from the Josephson device. The curve of critical current I_m versus control current I_c is known as the gain curve of the device. Such devices have been used as switching elements of logic circuits. For a given gating current I_g applied to a Josephson device, the control current I_c is varied to raise and lower the critical current I_m relative to the gating current. This causes the Josephson device to switch from the $V = 0$ to the $V \neq 0$ state.

It has been shown by D. E. McCumber in the Journal of Applied Physics, vol. 39, pg 3113, June 1968, that the time averaged voltage, V , across Josephson devices satisfying the equation,

$$1. CR^2 I_m < \Phi_0 / 2\pi,$$

is related to the current, I_g , flowing through the device by,

$$2. V^2 = R^2 [I_g^2 - I_m^2], \text{ where}$$

C = device capacitance;

R = total damping resistance across the device;

I_m = Josephson threshold current; and

Φ_0 = magnetic flux quantum.

Josephson devices satisfying equation (1) above are heavily damped and have a single valued $I - V$ characteristic (i.e., no hysteresis in the $I - V$ curve). Typical examples of Josephson devices satisfying equation (1) are junctions, constrictions and point contacts. It will be appreciated that Josephson devices can be made to satisfy equation (1) by adding a resistor across the junction.

By placing an external resistive load R_L across the device, the time averaged current I_L through said load is given by

$$3. I_L^2 = \frac{R^2}{R_L^2} (I_g^2 - I_m^2)$$

With a control current I_c applied, and since I_m is a function of I_c , i.e., $I_m = L(I_c)$, the load current is defined as,

$$4. I_L = \frac{R}{R_L} \sqrt{I_g^2 - L^2(I_c)}$$

In many Josephson devices I_m varies greatly for small variations in I_c . The actual functional relationship between I_m and I_c depends upon device configuration and geometry as well as on the effect of self-field either intrinsic or obtained through magnetic feed-back. Furthermore, as taught in U.S. Patent No. 3,764,863 issued on Oct. 9, 1973 which matured from Pat. Ser. No. 158,315, filed by Zappe on June 30, 1971 and entitled, "High Gain Josephson Device," the gain curve, or functional relationship between I_c and I_m , can be tailored, and even made linear for finite variations in I_c , i.e., the function can be tailored to achieve,

$$5. I_m = K I_c,$$

15 for finite variations of I_c . For some Josephson devices with large current densities, equation (5) is satisfied without the need for additional tailoring.

From equations (4) and (5) it will be appreciated that a Josephson device circuit having an input current 20 I_c and an output I_L , where,

$$6. I_L = \frac{R}{R_L} \sqrt{I_g^2 - K^2 I_c^2},$$

will act as an amplifier with essentially unlimited gain. However, despite the linear relationship between I_c and I_m , the circuit remains nonlinear.

SUMMARY OF THE INVENTION

In accordance with the present invention, a wide band linear amplifier is provided comprising a two stage Josephson circuit. The input to the amplifier is provided as a control current to a first Josephson device which is heavily damped and has a linear gain curve for finite variations of the control current. The load current through a resistor in parallel with the first Josephson device, is applied as a control current to a second Josephson device which also is heavily damped and has a linear portion in its gain curve. The resulting load current through a resistive load in parallel with the second Josephson device will be linearly related to the input current I_c provided the ratio of the gate currents applied to the second and first Josephson devices is set 40 approximately equal to

$$\frac{kR_1}{R_L},$$

50 where k is the slope of the gain curve of the second Josephson device in the operation region, R_1 is the damping resistance of the first Josephson device, and R_L is the load resistance in parallel with the first Josephson device.

BRIEF DESCRIPTION OF THE DRAWINGS

FIG. 1 illustrates a wide band linear amplifier constructed according to the teaching of this invention.

FIGS. 2a and 2b are graphs of gain curves for the Josephson devices illustrated in FIG. 1.

DETAILED DESCRIPTION OF THE PREFERRED EMBODIMENT

65 The preferred embodiment of the invention is illustrated in FIG. 1 and comprises two Josephson device circuits. The first Josephson device circuit comprises,

Josephson junction 20, formed by superconductors 24, 26 and tunnelling oxide 36. The circuit also includes superconductor 24, 26, 28 32 and 30, resistive load 34, and control current superconductor 38. The second circuit comprises Josephson junction 22 formed by superconductors 44 and 42 and tunnelling oxide 40. The second circuit further comprises superconductors 42, 44, 46 and 48 and resistive load 60. The current through superconductor 32 operates as control current for Josephson junction 22. An additional control carrying superconductor 50 may also be provided to carry a biasing control current as will be explained in greater detail hereafter.

The superconductors 38, 32 and 50 overlay and are insulated from the respective Josephson devices as is well known in the art. Also, as is well known in the art, the circuit illustrated overlies and is insulated from a ground plane, not shown. The Josephson devices 20 and 22 are heavily damped, i.e., satisfy equation (1) above, and have a linear relationship between I_c and I_m over a finite range of I_c , i.e., satisfy equation (5) above.

A general explanation of the wide band linear amplification of the circuit will now be described using subscripts 1 and 2 to designate parameters of the first and second stages respectively.

The critical current I_{m_1} for the first stage Josephson device is given by,

$$7. I_{m_1} = kI_{c_1},$$

where I_{c_1} is the input control current and k is a constant.

From equations (3) and (7), the load current, I_{L_1} , through resistor 34 becomes,

$$8. I_{L_1}^2 = \frac{R_1^2}{R_{L_1}^2} I_{g_1}^2 - \frac{R_1^2}{R_{L_1}^2} k^2 I_{c_1}^2,$$

where R_1 is the total damping resistance of Josephson device 20, R_{L_1} is the load resistance 34, and I_{g_1} is the gating current applied to the circuit.

The critical current, I_{m_2} , of the second Josephson device 22 is,

$$9. I_{m_2} = KI_{c_2} = KI_{L_1},$$

where K is a constant and I_{c_2} is the control current. The load current, I_{L_2} , through resistance 60, thus satisfies the equation,

$$10. I_{L_2}^2 = \frac{R_2^2}{R_{L_2}^2} I_{g_2}^2 - \frac{R_2^2}{R_{L_2}^2} K^2 I_{L_1}^2,$$

where R_2 is the damping resistance of Josephson device 22, R_{L_2} is the load resistance 60, and I_{g_2} is the gating current applied to the second stage.

Substituting for $I_{L_1}^2$ from equation (8), we obtain,

$$11. I_{L_2}^2 = \frac{R_2^2}{R_{L_2}^2} I_{g_2}^2 - \frac{R_2^2}{R_{L_2}^2} k^2 \frac{R_1^2}{R_{L_1}^2} I_{g_1}^2 + \frac{R_2^2}{R_{L_2}^2} k^2 \frac{R_1^2}{R_{L_1}^2} k^2 I_{c_1}^2.$$

If we choose the ratio of the drive currents to be,

$$\frac{I_{g_2}}{I_{g_1}} = K \quad \frac{R_1}{R_{L_1}}$$

the output current I_{L_2} becomes,

$$5 \quad I_{L_2} = \frac{R_2 R_1 K k}{R_{L_2} R_{L_1}} I_{c_1}.$$

Thus, the output current I_{L_2} is linearly related to I_{c_1} . Since it is possible to obtain $(K) (k) \gg 1$, the ratio of total damping resistance, $R_2 R_1$, to total load resistance, $R_{L_2} R_{L_1}$, can be made small compared to 1 and still result in high gain. However, the higher the ratio, the higher the gain.

The bandwidth of the amplifier is very large since current changes will occur with a time constant,

$$C'R < \frac{\phi_0}{2\pi R I_m}.$$

20 with $R \approx 0.02$ and $I_m \approx 30$ mA, $RC \approx 10^{-12}$ sec.

As is well known, Josephson devices produce Josephson oscillations at approximately 500MHz/ μ V. Since we are operating in the millivolt range, the Josephson oscillations will be at approximately 500 gigahertz. It 25 may not be necessary to filter out these oscillations, but standard high frequency filtering techniques may be used to damp the Josephson oscillations. One particular known technique for accomplishing the filtering is to provide wavy construction of superconductor lines 30, 28, 46 and 48 as illustrated in FIG. 1. Assuming that the attenuation of the Josephson components requires a maximum time constant of 10^{-11} seconds, we obtain a bandwidth of the circuit varying from d.c. to approximately 30 gigahertz.

35 A more specific example of the Josephson device linear amplifier will now be described with reference to FIGS. 1, 2A and 2B. For purposes of this explanation, the two Josephson devices are substantially identical and their gain curves are illustrated in FIGS. 2A and

40 2B, respectively. In each of FIGS. 2A and 2B, the polarity of I_g determines whether the portion of the gain curve above or below the abscissa is the operating portion of the gain curve. In FIG. 2A, representing device 20, curve 10 represents the operating portion, whereas

45 in FIG. 2B, representing device 22, curve 12 represents the operating portion of the gain curve. Curves 10 and 12 are identical except that the respective gating currents are assumed to be positive and negative, respectively. Referring to FIG. 1, the direction of I_{g_1} is assumed to be the positive current direction, and the direction of I_{g_2} is assumed to be the negative current direction.

This applies to control currents as well as gating currents. It can be seen from FIGS. 2A and 2B that, over limited I_c ranges, the gain curves are linear. The 50 gradual slopes of curves 10 and 12 each have a magnitude of ≈ 1 ; the steeper slopes have magnitudes = K .

55 In this example, the gate currents are selected to satisfy the equation:

$$60 \quad \frac{I_{g_2}}{I_{g_1}} = (K) \quad \left(\frac{R_1}{R_{L_1}} \right) = (-1) (1) = -1.$$

i.e., R_{L_1} is selected $\approx R_1$, I_{g_1} and I_{g_2} have the same magnitude, and k is -1 .

65 Since the gate current I_{g_1} flows in the positive direction, the curve 10 represents the gain curve for I_{m_1} . A bias control current I_{b_1} is selected to place the operat-

ing point of the device at $I_{m1} = I_o$ for no input current I_{in} . The bias current, which is a negative control current having a value I_{b1} , may be applied via control current superconductor 38 or via a separate bias current superconductor overlaying and insulated from Josephson device 20. The input current, I_{in} , thus will vary I_{m1} along the steep positive slope and

$$I_{m1} = I_o + K I_{in},$$

where K is the slope of the gain curve and $K \gg 1$. The load current through R_{L1} is

$$I_{L1} = \sqrt{I_{g1}^2 - I_{m1}^2},$$

$$I_{L1} = \sqrt{I_{g1}^2 - (I_o + K I_{in})^2}$$

The gate current through the second device is also selected as described above to be equal to $-I_{g1}$.

The bias I_{b2} is selected as shown in the graph. Since the slope of the curve 12 is -1 , it can be seen that

$$I_{m2} = -(1)(I_{L1}) = -I_{L1}$$

It should be understood that in the absence of input current I_{in} , the current I_{L1} due to the bias I_{b1} , above, plus the negative bias I_{b2} places the operating point of the gain curve 12 along the negative slope, for example at point 14.

From earlier equations,

$$I_{out} \sqrt{I_{g1}^2 - I_{m2}^2};$$

if $R_{L2} \approx R_2$;

$$I_{out} \sqrt{I_{g1}^2 - I_{L1}^2}$$

$$I_{L1}^2 = I_{g1}^2 - (I_o + K I_{in})^2$$

$$I_{out} \sqrt{I_{g1}^2 - I_{g1}^2 + (I_o + K I_{in})^2}$$

$$I_{out} = I_o - K I_{in}$$

Thus, the input signal is amplified by K and may be of either polarity since it is centered about I_o . To suppress I_o is well known in the art since a d.c. bias at the output occurs in almost all amplifiers.

Since the circuit shown in FIG. 1 behaves essentially as a transistor, it is also able to perform all of a transistor's circuit functions. It can thus be used to construct not only amplifiers but oscillators, flip-flops, single shots, etc. Additionally, it should be noted that because of the low operating temperature (4°K) the signal to noise ratio will exceed that of any device with comparable bandwidth.

What is claimed is:

1. A wide band linear amplifier comprising,
- a. first and second Josephson devices, each having a gain curve which is linear over a finite range of control current, and each being heavily damped and having damping resistances R_1 and R_2 respectively,
- b. a first superconducting circuit including said first Josephson device and further comprising a superconducting path having a load resistance R_{L1} therein in parallel circuit arrangement with said first Josephson device, and further superconductors for carrying a gating current I_{g1} to said parallel arrangement,
- c. a second superconducting circuit including said second Josephson device and further comprising a superconducting path having a load resistance R_{L2} therein in parallel circuit arrangement with said second Josephson device, and further supercon-

ductors for carrying a gating current I_{g2} to said parallel arrangement,

- d. said superconducting path having load resistance R_{L1} therein being positioned so that a portion thereof overlies said second Josephson device in a direction parallel to the direction of current flow through said second Josephson device, and
- e. an input control current superconductor for carrying input control current positioned to overlie said first Josephson device parallel to the direction of current flow through said first Josephson device.

2. A wide band linear amplifier as claimed in claim 1 wherein the gating currents I_{g1} and I_{g2} satisfy the condition,

$$\frac{I_{g2}}{I_{g1}} \approx K \frac{R_1}{R_{L1}}$$

20 where K is the slope of a portion of the gain curve of said second Josephson device.

3. A wide band linear amplifier as claimed in claim 2 wherein each of said first and second Josephson devices satisfies the equation,

$$CR^2 I_m < \Phi_0 / 2\pi,$$

where, C is the device capacitance,

R is the total damping resistance across the device, I_m is the Josephson threshold current, and Φ_0 is the magnetic flux quantum.

30 4. A wide band linear amplifier as claimed in claim 3 further comprising separate bias control current superconducting means for carrying a bias control current for said second Josephson device, and means overlaying said second Josephson device in a direction parallel to the current direction through said second Josephson device.

35 5. A wide band linear amplifier as claimed in claim 4 wherein said parallel superconducting paths having said load resistances R_{L1} and R_{L2} therein, respectively, further include ultra high frequency filtering means for removing Josephson oscillations from the load current flowing through said load resistances R_{L1} and R_{L2} .

40 6. An apparatus comprising:
first and second devices in which Josephson current can flow, said devices exhibiting substantially no hysteresis when switched, each device having a gain curve which is linear over a finite range of control current and each of which is heavily damped by an external resistance, said devices having first and second total damping resistances R_1 and R_2 respectively,

a first circuit including said first device and having a load resistance R_{L1} therein, said first circuit being connected to said first device,

a source of a gating current I_{g1} for providing current through said first device,

a second circuit including said second device and having a load resistance R_{L2} therein, said second circuit being connected to said second device,

a source of a gating current I_{g2} to said second device, said first circuit connected to said first device being positioned so that current through said first circuit controls said second device and,

means for providing control signals for regulating said first device.

65 7. The apparatus of claim 6, wherein the gating currents I_{g1} and I_{g2} satisfy the condition

$$I_{g2}/I_{g1} \approx K(R_1/R_{L1}),$$

where K is the slope of a portion of the gain curve of said second device.

8. The apparatus of claim 7, wherein said first and second devices are damped by the resistances R_{L1} and R_{L2} , respectively. 5

9. The apparatus of claim 8, where said first and second devices satisfy the inequality.

$$CR^2I_m < \Phi_0/2\pi,$$

where C is the device capacitance,

R is the total damping resistance across each device, I_m is the maximum current through each tunnel device, and

Φ_0 is the magnetic flux quantum.

10. The apparatus of claim 6, wherein said first and second circuits include filtering means for removing Josephson oscillations from the currents which flow through said load resistances R_{L1} and R_{L2} . 15

11. An apparatus comprising:

a first device capable of supporting Josephson current therethrough, said first device being connected to a first circuit having a resistance R_{L1} which heavily damps said first device wherein the total damping resistance of said first device is R_1 , 25
a second device capable of supporting Josephson current therethrough, said second device being connected to a second circuit having a resistance R_{L2} which heavily damps said second device, means for providing electrical currents I_{g1} through said first device and I_{g2} through said second device, where the ratio I_{g2}/I_{g1} bears a linear relationship to 30

the ratio R_1/R_{L1} , control means for switching said first device to transfer at least a portion of said current I_{g1} into said first circuit, wherein said first circuit is positioned with respect to said second device that current in said first circuit controls said second device.

12. The apparatus of claim 11, where said first device has a maximum Josephson current I_{m1} and said control means carries a current I_{c1} , where I_{m1} is a linear function of I_{c1} over a range of I_{c1} .

13. The apparatus of claim 12, where said second device has a maximum Josephson current I_{m2} which is linearly related to the magnitude of said control magnetic field over a range of said control magnetic field.

14. The apparatus of claim 13, further including means for filtering Josephson oscillations from the currents flowing through said load resistances R_{L1} and R_{L2} .

15. An apparatus comprising:
a first device capable of supporting Josephson tunneling current therethrough said first device being connected to a first circuit having a resistance R_{L1} ,
a second device capable of supporting Josephson tunneling current therethrough said second device being electrically connected to said first circuit and to a second circuit having a resistance R_{L2} associated therewith,
wherein said first and second devices exhibit substantially no hysteresis when switched, and
control means for switching said devices.

16. The apparatus of claim 15, where said resistance R_{L1} heavily damps said first device and said resistance R_{L2} heavily damps said second device.
